KNOCKDOWN STEEL SHELVING SUPPORT

Irwin J. Ferdinand, Glencoe, and Irwin R. Kulbersh, Niles,
Ill., assignors to S. A. Hirsh Manufacturing Company,
Skokie, Ill., a corporation of Illinois

Filed Dec. 18, 1967, Ser. No. 9,818

Term of patent 14 years

Int. Cl. D25—03

U.S. Cl. D13—1

FIG. 1 is a front elevational view of a knockdown steel shelving support showing our new design in full lines;

FIG. 2 is a cross-sectional view thereof and same being of uniform section throughout its length;

FIG. 3 is a side elevational view, the opposite side being substantially a mirror image thereof; and

FIG. 4 is a rear elevational view thereof.

The dotted line showing in FIGS. 1 and 2 is for illustrative purposes only.

We claim:

The ornamental design for a knockdown steel shelving support, as shown and described.
